UNITED STATES PATENT OFFICE.

CARL BARTELS AND CLAYTON J. GOEBEL, OF HAMILTON, OHIO, ASSIGNEES TO THE MOSLER SAFE COMPANY, OF HAMILTON, OHIO, A CORPORATION OF NEW YORK.

SAFETY DEVICE FOR VAULTS, SAFES, AND THE LIKE.

Original application filed February 2, 1924, Serial No. 690,124. Divided and this application filed July 29, 1925. Serial No. 46,719.

This invention relates to safety devices for vaults, safes and the like, and more particularly to means operable from the interior of the structure for admitting air to a person locked inside of the structure.

This application is a division of an application filed by ourselves February 2, 1924, for improvements in safety device for vaults, safes and the like, Serial No. 690,124.

At the present day, many persons, principally bankers, are much concerned about being waylaid by burglars and forced into a safe or vault and having the door closed and locked upon them, in which case they are subjected to the danger of being suffocated due to the lack of means for allowing air to enter the structure when it is locked.

The principal object of our invention is to provide a device which is adapted to be associated with a vault, safe or similar structure, and which is operable from the inside of the structure to open an air passageway from the exterior to the interior of the structure without requiring the structure to be unlocked and opened.

A further object of our invention is to provide means of the character described which are not operable from the exterior of the structure.

Other objects of our invention will be in part obvious and in part pointed out hereinafter.

In order that a clearer understanding of our invention may be had, attention is hereinafter directed to the accompanying drawings, forming a part of this application and illustrating one possible embodiment of our invention.

Referring to the drawings, Fig. 1 is a sectional view through a safe wall showing the safety device mounted therein; Fig. 2 is an end view of the device showing the exterior end thereof; and Fig. 3 is a plan view of the interior end of the safety device, a portion of the hand wheel being shown broken away to more clearly bring out the construction. Similar reference characters refer to similar parts throughout the several views of the drawings.

The safety device consists primarily of an air passageway through one of the enclosing walls of the structure and a plug removably filling the passageway, the plug being removable from the passageway by

manual manipulation from the interior of the structure to open an air passageway from the exterior to the interior of the structure. The plug is not removable from the exterior of the structure.

Referring to the drawings, a steel block 1 is mounted in the concrete safe wall 2, so as to extend from the inner surface to the outer surface thereof. The inner end of the block 1 extends inwardly beyond the inner surface of the wall 2, and is there provided with external threads 3 and with an interior threaded recess 4. The threaded hub 5 of a hand wheel 6 normally engages the threads of recess 4. Block 1 has an axial passage therethrough contoured to receive a rod-like plug 8, which toward its rear end has an enlarged portion 9 seated in a correspondingly enlarged portion of the passage through block 1. The rear portion of this plug penetrates the hub 5 axially, and a nut 11 is screwed on a reduced threaded portion on the end of the plug, the nut preferably having a tapered recess in which the plug end is subsequently flattened, as at 10. The plug 8 cannot be driven inwardly by reason of the abutment of enlarged plug portion 9 against the hub 8, which is in threaded engagement with the block 1. A nut 12 and a lock nut 13 are screwed upon the inner end of the block 1 to prevent this block from being pulled out from the front, and the front end of the block 1 is flanged outwardly, as at 14, to prevent the block from being driven inwardly from the front.

To open communication through the vault wall with this device, it is merely necessary to rotate the hand wheel 6 until its hub 5 is released from the threads of the block 1 and then to pull the plug 8 out of the block. The nut 11 prevents the hub from leaving the plug rearwardly.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What we claim is:

1. The combination with a vault wall, of a block mounted therein and having a safety

- aperture therethrough, the rear end of said block being threaded and exposed on the inner side of the vault wall, a member engaging said threads and abutting the vault wall, whereby the block is held against forward removal from said wall, a plug in the safety aperture, and means for retaining the plug in said aperture against removal rearwardly therefrom.

2. The combination with a vault wall, of a block mounted therein and having a safety aperture therethrough, the rear end of said block being threaded and exposed on the inner side of the vault wall, and a member engaging said threads and abutting the vault wall, whereby the block is held against forward removal from said wall, said block having a lateral projection engaging the vault wall, whereby the block is held against rearward removal from said wall, a plug in the safety aperture, and means for retaining the plug in said aperture against removal rearwardly therefrom.

3. The combination with a vault wall, of a block mounted therein and having a safety aperture therethrough, the rear end of said block being threaded and exposed on the inner side of the vault wall, a member engaging said threads and abutting the vault wall, whereby the block is held against forward removal from said wall, a plug fitting in said aperture, and a retaining member removably engageable with the plug and block whereby the plug may be releasably confined in said aperture against rearward removal therefrom.

4. The combination with a vault wall, of a block mounted therein and having a safety aperture therethrough, the rear end of said block being threaded and exposed on the inner side of the vault wall, a member engaging said threads and abutting the vault wall, whereby the block is held against forward removal from said wall, a plug fitting in said aperture, and a retaining member removably engageable with the plug and block whereby the plug may be releasably confined in said aperture against rearward removal therefrom.

5. The combination with a vault wall, of a block mounted therein and having an aperture extending from one end to the other thereof, a plug removably mounted in said aperture, a hand wheel exposed on the inner side of the vault wall and having a hub encircling said plug and in threaded engagement with said block, the inner end of said block being threaded and exposed on the inner side of said wall, and a nut screwed on said inner end of the block and against the wall, whereby forward movement of said block in said wall is prevented.

6. The combination with a vault wall, of a block mounted therein and having an aperture extending from one end to the other thereof, a plug removably mounted in said aperture, a hand wheel exposed on the inner side of the vault wall and having a hub encircling said plug and in threaded engagement with said block, said block having a flange portion at its outer end, whereby rearward movement of said block in said wall is prevented.

This specification signed this 1st day of July, 1925.
